(57) **CLAIM**

The ornamental design for a LED string light, as shown and described.

DESCRIPTION

FIG. 1 is a front, right, top perspective view of a LED string light, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of detail 9 in FIG. 1;

FIG. 10 is an enlarged view of detail 10 in FIG. 1;

FIG. 11 is an enlarged view of detail 11 in FIG. 2;

FIG. 12 is an enlarged view of detail 12 in FIG. 2;

FIG. 13 is an enlarged view of detail 13 in FIG. 3;

FIG. 14 is an enlarged view of detail 14 in FIG. 5;

FIG. 15 is an enlarged view of detail 15 in FIG. 7;

FIG. 16 is a front, right, top perspective view of the LED string light shown in use;

FIG. 17 is an enlarged view of detail 17 in FIG. 16; and,
FIG. 18 is an enlarged view of detail 18 in FIG. 16.

The dashed broken lines in the figures are for the purposes of illustrating portions of the LED string light and form no part of the claimed design.

The dash-dot-dash broken lines in FIGS. 1-3, 5, 7, and 9-18 delineate areas of the figures shown enlarged and form no part of the claimed design.

The other broken lines, shown only in FIG. 16, FIG. 17 and FIG. 18, are for environmental purposes only and form no part of the claimed design.

1 Claim, 18 Drawing Sheets
